WALL CONSTRUCTION

Harry Holdsworth, Bronxville, N. Y., assignor to
 Holdsworth Bros., Inc., New York, N. Y., a corporation of New York

Application August 5, 1938, Serial No. 223,196

5 Claims. (CL 72—46)

My invention relates to a new and improved wall or partition construction, and an improved method of making the same.

One of the objects of the invention is to provide a construction which can be manufactured and erected with a great saving in labor cost.

Another object of the invention is to provide a pre-fabricated base for a wall or partition construction, said base being of the type which can be manufactured at low cost.

Another object is to produce a pre-fabricated base which will cooperate with the other elements of a wall or partition, to produce a simple and rigid construction which can be erected with a great saving in labor cost.

Another object of the invention is to provide a pre-fabricated base for a wall or partition which will include a member with which the vertical columns are adapted to interfit, said member being combined with laterally spaced base members, which may be moldings or which may be a different type.

Another object is to provide a unit or assembly which acts as a base for the two sides of a partition, as a ground for plaster, and as a floor member for securing the bottom ends of the studs.

Other objects of my invention will be set forth in the following description and drawings which illustrate several preferred embodiments thereof, it being understood that the above statement of the objects of my invention is intended generally to explain the same without limiting it in any manner.

Fig. 1 is a side elevation, partially in longitudinal section, showing the improved base and a vertical column associated therewith. Part of the representation of the base has been omitted in this figure, in order to show the construction clearly.

Fig. 2 is a top plan view of the pre-fabricated base.

Fig. 3 is a sectional view on the line 3—3 of Fig. 1.

Figs. 4—7 inclusive are views generally similar to Fig. 3, showing respectively different embodiments of the invention.

Fig. 8 is a sectional view in a vertical plane, showing a different embodiment of the invention, which applies particularly to finishing an exterior wall.

Fig. 9 is a view similar to Fig. 8, showing a modification thereof.

Fig. 10 is a sectional view which illustrates a further modification of the invention.

Fig. 11 is a front elevation taken at the left-hand side of Fig. 10.

Fig. 12 is a front elevation taken at the right-hand side of Fig. 10.

Fig. 13 illustrates an additional modification in which there are two rows of upright columns or the like in the wall or partition.

Fig. 14 illustrates an additional modification.

Fig. 15 is a sectional view on the line 15—15 of Fig. 14.

Fig. 16 is a perspective view, showing one of the structural elements of one type of the improved base.

Fig. 17 illustrates a modification in which the base is made of an integral piece of metal. This is a section on the line 17—17 of Fig. 18.

Fig. 18 is a top plan view of the construction shown in Fig. 17.

Fig. 19 is a top plan view showing a modified base, which is made from a single sheet of metal.

Heretofore, in erecting a wall or partition, it has been suggested to interfit vertical channels with a metal strap having recesses. Whenever a wall or partition is constructed, it is usually necessary to provide a base which is made of wood or metal or cement, so as to prevent the plaster of the wall or partition from contacting with objects which are moved along the floor of the room.

According to the previous practice, the manufacture of the base was extremely expensive. If the base were made of wood, it was necessary to construct a wood ground, prior to the application of the plaster to the wall or partition. This wood ground consisted of a horizontal strip of wood which was nailed or otherwise secured to the frame-work of the wall or partition. This wood ground served as a guide for the application of the plaster to said frame-work and also to secure the wood base which was applied to the wall after the plaster had been applied. After the wood ground had been located on each side of the frame-work of the partition, the plaster was then applied to the frame-work and the plaster was allowed to set or harden. The wood base or moulding was then nailed or otherwise secured to the previously assembled wood ground, thus completing the wall or partition.

If a metal base or moulding was required, it could be erected according to the method previously described. Another method was to connect clips to the floor or to the frame-work of the partition, prior to applying the plaster to the frame-work. Separate metal base-members or mouldings were then connected to these clips.

The plaster was then applied and allowed to set. In all of these old methods, the base-members were wholly separate and independent of each other and it was necessary to apply them separately, on each side of the wall or partition.

The second-described method of providing a metal base was more economical than the first-described method, but even the second-described method required three operations, namely, connecting the claps to the frame-work of the partition or of the floor and then connecting separate metal members to said claps on each side of the partition.

According to the construction shown herein, the two sides of the base are connected to each other, as a pre-fabricated unit, and such unit can readily be made at low cost at the factory. This unit may include means which interfit with the vertical columns. It is therefore merely necessary for the workman to erect the vertical columns and then to complete the frame-work of the partition in the usual manner. It is then merely necessary to apply the plaster, and the work is necessarily absolutely accurate, whereas in hand work inaccuracies may sometimes occur.

As shown in Figs. 1 and 3, the first embodiment of the invention comprises outer body members 1 and 2. These body members 1 and 2 are made of metal or other suitable material. These body members have substantially vertical walls which have inturned top flanges 1a and 2a. These top flanges are substantially horizontal, and the junction of said flanges with the vertical walls of said body members 1 and 2 may be curved. The invention is not limited to any particular shape or size of the members 1 and 2. A longitudinal metal strap 3, having recesses 4, is connected to the body members 1 and 2, in any suitable manner. For example, planar portions of the longitudinal strap 3 may be connected by spot-welding or in any suitable manner to the horizontal planar transverse legs of U-shaped brackets, which are spaced longitudinally from each other. The vertical planar legs of said brackets 5 abut the inner surfaces of the vertical walls of members 1 and 2. The vertical planar legs of brackets 5 and the vertical planar walls of the body members 1 and 2 can be connected by spot-welding or in any other suitable manner. The planar connecting portions of the strap 3 overlie the horizontal legs of the brackets 5. Holes may be provided in the intersecting and connected portions of the strap 3 and of the horizontal legs of the brackets 5, and nails 6 or other fastening members may be driven through said holes into the floor F. The brackets 5 are preferably provided at the ends of strap 3, and also intermediate said ends, if desired.

Upright columns 7, which may be metal channels, may be located as shown in Fig. 2, with the main webs of said columns 7 interfitting with the recesses 4. Referring to Fig. 2, the side walls of the columns 7 may snugly abut the longitudinal edges of the metal straps 3, but I prefer to have a little lateral play between strap 3 and columns 7.

When the columns 7 are located as shown in Fig. 2, the upper ends of the columns can be suitably connected to the ceiling or to any member which depends from the ceiling. The frame of the wall or partition can then be completed, if desired, by connecting metal mesh or metal lath 8 to the columns 7 in any suitable manner. These details of finishing the wall or partition are not shown, as they are well known.

Fig. 3 is substantially the same as Fig. 2, save that the body members 1 and 2 have flanges 1a and 1b which are bent so as to form substantially sharp edges or corners with the metal members 1 and 2. Fig. 3 also shows the metal lath 8 which is suitably connected to the respective columns 7, and it also shows the plaster P on each side of columns 7.

Fig. 3 shows a flush type of partition, in which the outer planar vertical surfaces of the plaster are flush with the outer planar vertical surfaces of the metal body members 1 and 2.

Fig. 4 shows a type of partition in which the base projects laterally beyond the vertical outer surfaces of the plaster P. Otherwise Fig. 4 is the same as the embodiment of Figs. 1 and 2.

Fig. 5 is substantially the same as Fig. 4, save that it shows the body members 1 and 2 provided with flanges 1c and 1d which are known in the trade as "mouldings".

The spot-welding which is designated in Figs. 3, 4 and 5 by the legend "Spot weld" may mar the outer surfaces of the vertical walls of the body members 1 and 2.

Therefore in Fig. 6 I have shown the body members of the base consisting of rolled metal sections 9 and 10, said sections respectively having integral bottom flanges 9a and 10a. Transverse metal bars 11 are spot-welded to the bottom flanges 9a and 10a at longitudinally spaced points, and the strap 4, which has the same construction as shown in Fig. 2, has planar portions which are spot-welded to said transverse planar metal bars 11. In this embodiment, the tops of the body members 9 and 10 are provided with hook-shaped metal flanges 9b and 10b, which are engaged at intervals by U-shaped reinforcing arms 12 which may be spot-welded or otherwise secured to the inner walls of said hook-shaped flanges 9b and 10b. If desired, the vertical arms of the U-shaped arms 12 can have a drive fit into the hook-shaped flanges 9b and 10b. This produces a rigid and sturdy base structure, whose visible parts are not marred by spot-welding.

Fig. 7 is substantially the same as Fig. 6, save that the members 9 and 10 have their bottom flanges provided with upstanding arms 14 and 15. These upstanding arms 14 and 15 are connected at spaced intervals by metal bars 16 having the angular cross-section shown in Fig. 7. The metal bars 16 may be spot-welded to or they may interlock tightly with the body members.

Fig. 8 shows the outer wall 18 of a building, which may be masonry or the like. A metal base member 19 is connected by spot-welding to a bracket 20, which has two vertical legs and an intermediate horizontal web. This bracket 20 is connected to the wall by means of nails or other fastening members 21. The members 19 and 20 can be assembled or pre-fabricated at the factory. After this assembled unit has been suitably connected to the wall, plaster P is applied to the inner surface of the wall in order to cover the top leg of bracket 20, and to finish the wall.

Fig. 9 shows an improved structure whereby the plaster is spaced from the inner surface of the outer wall by an air space, in order to prevent moisture from entering the plaster. In Fig. 9, the body member 22, having the top flange 23, is spot-welded to an angular web 24. The strap 4 shown in Fig. 2 has its flat or planar ends spot-welded or otherwise secured to the bottom flange of the web 24. The columns 7 in this construction abut the inner surface of the outer wall 18, and the metal mesh or metal lath 8 is connected

to said columns at their inner faces. The plaster P is then applied. The columns 7 therefore form an air space between the inner surface of the wall and the adjacent surface of the plaster P.

5 Fig. 10 shows a construction substantially similar to that shown in Figs. 4 and 5, save that it shows body members 25 and 26 which are of different heights, and the intermediate supporting brackets also have vertical legs 27 and 27a of different heights.

Fig. 13 is substantially the same as Fig. 2 and Fig. 4, save that Fig. 13 shows a plurality of base straps 3 and a plurality of rows of columns 7.

Referring to Figs. 14 and 15, the rolled metal strap 3, having the recesses 4, is replaced by a metal channel 28. The vertical walls of said channel 28 have their bottom edges connected by spot-welding or in any other suitable manner to brackets 5, which are substantially the same as the brackets 5 shown in Fig. 2. The columns 7 rest on the horizontal web of base-channel 28.

Fig. 16 shows a channel 28a, whose main web has slots 29. This can be used in place of channel 28 in Fig. 14. The columns 7 then substantially interfit with the walls of slots 29.

Fig. 17 shows a base made of an integral rolled piece of metal. This base has vertical walls 30, 31, which have hook-shaped flanges 30a, 31a, and a bottom wall having marginal horizontal wall-portions 32 and 33 and a central U-shaped wall-portion having slots 34. The slots 34 have the same function as the slots 29 shown in Fig. 16. When columns 7 are assembled with the base shown in Fig. 17, the bottoms of the columns rest on the floor.

In Figs. 17 and 18 the bottom wall-portions 32 and 33 are continuous along the length of the base member. In Fig. 19 the vertical members 30 and 31 are connected at intervals by U-shaped members 34b having the slots 34.

40 In every embodiment the entire base, including the base member with which the vertical columns interlock or on which the vertical columns rest (as in the case of Fig. 14) is pre-fabricated as a complete assembly at the factory. The strap 3 or the equivalent members disclosed in the other drawings may be omitted without departing from the invention as long as the base has two longitudinal base members rigidly connected in spaced relation.

50 In the embodiment of Figs. 14 and 15, the columns 7 can be connected to the channel base 28, by means of clips.

Whenever I refer to plaster, I include every finishing material which is applied to a wall or partition, and said finishing material may or may not be spreadable.

Referring to Figs. 3 and 8, the columns 7 in Fig. 3 and the wall 18 in Fig. 8 constitute vertical supporting means to which plaster or other finishing medium is applied. In each of said figures a base member has a vertical wall or walls which are spaced from said vertical supporting means.

60 In Figs. 2 and 17 and in all the other figures, save Figs. 8 and 9, the base consists of longitudinal body members interconnected and held in lateral spaced relation, either by the brackets 5 shown in Fig. 2, or by the integral connecting means shown in Fig. 17.

70 One of the great advantages of the construction shown in Fig. 2, is that said construction is particularly adaptable in making angular base-constructions. If a device is a continuous channel of the type shown in Fig. 17, it is necessary to connect two such channels to each other at

right angles, by means of welding or by forming an open mitre joint. In sharp distinction, it is very easy to form the body members 1 and 2 into angular shape by means of suitable dies, and then to connect said angular members to each other by means of the brackets 5. In such case each of the legs of the angular base-construction would have its own metal strap 3. Likewise the construction shown in Fig. 2 is adaptable for base-constructions of substantial width, as for example, where it is necessary to accommodate one or more pipes of large diameter within the wall or partition. Such pipes may be sewer pipes. In such case the brackets 5 can be made of suitable sufficient width, or else said brackets 5 could have their cross members made of relatively adjustable portions. Therefore the construction shown in Fig. 2 is very useful in meeting the various conditions which are encountered in erecting a building.

20 I claim:

1. A base for a wall or partition, said base comprising laterally spaced and longitudinal body members and connecting means rigidly connecting said body members in lateral spaced relation, said connecting means being integral with and being located below the tops of said body members, said connecting means having openings which are shaped to receive upstanding studs and to hold said studs against substantial longitudinal movement relative to said body members.

2. A base for a wall or partition, said base comprising laterally spaced and longitudinal body members and connecting means rigidly connecting said body members in lateral spaced relation, said connecting means being integral with and being located below the tops of said body members, said connecting means having an upstanding wall-portion which is located intermediate and below the tops of said body members, the top of said upstanding wall-portion having openings which are shaped to receive upstanding studs, and to hold said studs against substantial longitudinal movement relative to said body members.

3. In combination with a base for a wall or partition, said base comprising laterally spaced longitudinal body members, longitudinally spaced lateral connecting members rigidly connecting said body members in lateral spaced relation, a longitudinal member located intermediate said body members and held in fixed relation thereto, said intermediate longitudinal member having recesses which are spaced longitudinally, said recesses being shaped to receive upstanding studs, and to hold said studs against substantial longitudinal movement relative to said body members, plaster located in said base and above said base and exposing said body members.

4. A wall construction comprising laterally spaced longitudinal base members, longitudinally spaced lateral connecting members which are located intermediate said body members, said laterally spaced connecting members being rigidly connected to said body members to hold them in lateral spaced relation, a longitudinal member located intermediate said body members and held in fixed relation relative to said base members, said intermediate longitudinal member having recesses which are shaped longitudinally, upstanding studs having their bottom ends located in said recesses, the bottom ends of said studs being shaped to interfit with the walls of said recesses, plaster facing covering said studs, said

plaster facing being located between and above said longitudinal body members and exposing said body members.

5. A wall construction comprising laterally spaced and longitudinal base members, connecting means rigidly connecting said base members in lateral spaced relation, upstanding studs located intermediate said base members, said studs

being spaced longitudinally relative to each other, additional means located intermediate said base members and shaped and adapted to hold the lower ends of said upstanding studs against substantial longitudinal movement relative to said base members, plaster facing covering said studs, said plaster facing exposing said base members.

HARRY HOLDSWORTH.
